CLAIM

(57) The ornamental design for a connector, as shown and described.

DESCRIPTION

FIG. 1 is a front perspective view of a connector, showing our new design;

FIG. 2 is a front view thereof;

FIG. 3 is a rear view thereof;

FIG. 4 is a side view thereof;

FIG. 5 is an opposing side view thereof;

FIG. 6 is a top view thereof; and,

FIG. 7 is a bottom view thereof.

The broken line showings of the USB connector in FIGS. 1-6, the port in FIG. 7 and the various elements on the front and rear in all the figures are included for the purpose of illustrating unclaimed portions of the connector and form no part of the claimed design.
